UNITED STATES PATENT OFFICE.

ROY J. COOK, OF CHICAGO, ILLINOIS, ASSIGNOR OF ONE-HALF TO GEORGE C. MURRAY,
OF CHICAGO, ILLINOIS.

YOKE.

1,224,278.

Specification of Letters Patent.

Patented May 1, 1917.

Application filed March 13, 1914. Serial No. 824,504.

To all whom it may concern:

Be it known that I, Roy J. Cook, a citizen of the United States, residing at Chicago, in the county of Cook and State of Illinois, have invented certain new and useful Improvements in Yokes, of which the following is a specification.

This invention relates to improvements in yokes and more especially to the type of yoke used with railway draft rigging.

10 The object of this invention is to provide a new and improved yoke, together with allied elements coacting between such yoke and a coupler butt to provide a positive engagement against draft strains between the yoke and coupler. Another object is to provide a construction of the class described which will enable ready assembling and disassembling of the coupler and yoke.

20 These and other objects will be set forth in the following specification and as shown in the accompanying drawings, in which—

Figure 1 is a perspective view partly in section of my invention as applied to a rail-way car.

25 Fig. 2 is a perspective of the yoke.

Fig. 3 is a transverse section through the rigging and draft members of a car along the line 3,3 of Fig. 1; and

30 Fig. 4 is a side elevation drawn to a reduced scale showing the manner of assembling the coupler and yoke.

Like numerals refer to like elements throughout the drawings, in which 10 designates draft sills of a car carrying the cheek or draft plates 11 provided with suitable lugs for coaction with the usual form of follower plates. Carried between the cheek plates 11 is the yoke 12 having a rear 35 end 12^a against which abuts a follower 13. Other followers 13 are similarly carried between the arms of the yoke 12, and coil springs 14 coact therewith in the usual manner, the type of draft rigging shown being 40 that known as tandem in which two sets of followers and springs are used. At its forward end the yoke 12 is open, the ends of the arms of the yoke 12 being inwardly extended to form lugs 12^b (see Fig. 1) these lugs 12^b being inturned as shown in the drawings.

50 Wings 12^c extend between and are preferably formed integral with the forward ends of the arms of the yoke 12 (see Fig. 2). These wings 12^c are slotted at 12^d for a purpose to be hereinafter described. The wings

12^c serve to prevent spreading of the yoke arms at the open end of the yoke and thereby serve to maintain the inturned lugs 12^b in fixed relation. The coupler bar 15 is provided with the enlarged butt 15^a forming 60 the shoulders 15^b, as clearly shown in Figs. 1 and 4, for example. This coupler butt 15^a is of such dimensions as to enable its insertion between the inturned ends on lugs 12^b of the yoke when the device is assembled. 65 In such assembling before the draft rigging proper is placed in the yoke 12, the coupler is inserted, as stated, between the lugs 12^b and passed rearwardly in the yoke 12 to the position shown in Fig. 4, that is, rearwardly 70 of the side wings 12^c. When in this position what I term the key blocks 16 are placed in position, as shown in Fig. 4, whereupon the coupler bar is drawn out to position shown in Fig. 1 permitting the placing of 75 the draft rigging. Each of these key blocks 16 comprises the rearwardly extending portion 16^a and the enlarged forward end 16^b having the shoulder 16^c contacting with the shoulder 15^b of the coupler butt 15^a. The 80 head 16^b of each block 16 is of a size to substantially extend between the coupler bar 15 and the inner side of the adjacent arm of the yoke 12 and the body portion 16^a of such block extends substantially between the 85 coupler butt 15^a and the adjacent arm of the yoke 12. These blocks are constructed to fit as closely as possible while permitting a slight forward and back movement of the coupler relative to the yoke in this form of 90 tandem rigging in meeting the usual draft and buffing strains and shocks. It will be obvious that in applying my invention to the single rigging I may omit the key usually provided and rely upon these blocks 16 to 95 prevent accidental disassembling of the drawbar and yoke. The side wings 12^c will serve to prevent accidental displacement or side slip of the key blocks 16, as will be apparent, and the body portion 16^a thereof is 100 made of a sufficient length to prevent falling down or jamming of the blocks between the shoulder 15^b and the lugs or inturned ends 12^b. The depth and thickness of the heads 16^b is sufficient to provide a required strength 105 between the coupler butt and the yoke according to the strains and stresses met with in use.

The coupler bar 15 is apertured, as indicated at 15^e, and a key 17 is adapted to ex- 110

tend through the aperture 15^c as well as through the slots 12^d, the slots 12^d being of such size as to permit any sliding therein of such key 17, while the latter closely fits the 5 aperture 15^c in the coupler 15. Suitable slots are provided in the draft sills to permit sliding therein of the key 17. The slots 12^d are preferably arranged so that the key 17 will contact with the forward end there-
10 of at the same time the shoulders 15^b of the coupler butt 15^a begin to press against the heads of the filler block 16, forcing the latter against the lugs 12^b. It will be apparent by this means that the permitted stress or
15 strain on draft shocks may be greatly increased over the amount of the same permitted when merely the key construction is used and I may provide a greater factor of safety by increasing the depth of the head 16^b on
20 filler block 16 by slightly altering dimensions of the allied parts. Such necessary alterations may be readily made without interfering with the necessary limits as established by conventional car building practice.
25 These alterations may not be made beyond certain limits to increase the resisting strength in the key construction.

It is apparent that I may modify or alter dimensions or constructions shown without affecting the operation of my invention and I do not wish to be restricted to the form shown and described beyond the scope of the appended claims.

What I claim is:

30 35 1. In combination, a yoke having inwardly directed lug portions, a coupler hav-

ing a shouldered butt, the butt of said coupler being of such size as to permit the insertion thereof between said lug portions, key block members located between the 40 shoulders of said coupler butt and said lug portion, and means to normally prevent displacement of said key block members, said means being arranged to prevent spreading of the arms of said yoke adjacent said lug 45 portions, said last named means comprising wings integrally formed with and extending between the arms of said yoke.

2. In combination, a yoke having inwardly directed lug portions, a coupler having a shouldered butt, the butt of said coupler being of such size as to permit the insertion thereof between said lug portions, key block members located between the shoulders of said coupler butt and said lug 50 portion, means to normally prevent displacement of said key block members, said means being arranged to prevent spreading of the arms of said yoke adjacent said lug 55 portions, said last named means comprising wings integrally formed with and extending between the arms of said yoke, and means coacting with said coupler butt and said wings to substantially prevent rearward movement of the former relative to the latter.

In testimony whereof, I have subscribed my name.

ROY J. COOK.
